UNITED STATES PATENT OFFICE

155,777

DESIGN FOR AN AIRPLANE

Charles W. Butler, Leonia, N. J., assignor to The
Glenn L. Martin Company, Baltimore, Md.

Application October 28, 1947, Serial No. 142,175

Term of patent 14 years

(Cl. D71—1)

To all whom it may concern:

Be it known that I, Charles W. Butler, a citizen of the United States and resident of city of Leonia, county of Bergen, State of New Jersey, have invented a new, original, and ornamental Design for an Airplane, of which the following is a specification, reference being had to the accompanying drawings, forming a part thereof.

Figure 1 is a fragmentary perspective view of an airplane interior, showing the passenger lounge.

Figure 2 is a fragmentary sectional view showing the passenger lounge arrangement in plan.

Figure 3 is a fragmentary sectional view showing the passenger lounge arrangement in elevation.

Figure 4 is a top plan view of the entire airplane.

The characteristic features of my design reside

in the portions, especially of the interior, shown by means of full lines in the drawing.

I claim:

The ornamental design for an airplane, substantially as shown and described.

CHARLES W. BUTLER.
